CLAIM

The ornamental design for a double-ended flex handle
wrench, as shown as described.

DESCRIPTION

FIG. 1 is a top plan view of a double-ended flex handle
wrench embodying our new design;

FIG. 2 is an enlarged fragmented top plan view of the right
end thereof, the top plan view of the left end being a mirror
image;

FIG. 3 is an enlarged fragmented rear elevational view of the
right end thereof, the rear elevational view of the left end
being a mirror image;

FIG. 4 is an enlarged fragmented front elevational view of
the right end thereof, the front elevational view of the left
end being a mirror image;

FIG. 5 is a right side elevational view thereof; and,

FIG. 6 is a left side elevational view thereof.
